United States Patent Office

Des. 196,200
Patented Sept. 3, 1963

196,200

TRADING STAMP

William L. Howe, Hannibal, Mo., assignor to Gold Bond
Stamp Company, Minneapolis, Minn., a corporation of
Minnesota

Filed Nov. 6, 1961, Ser. No. 67,380

Term of patent 14 years

(Cl. D59—6)

Fig. 1.

Fig. 2.

FIGURE 1 is a front elevational view of a trading stamp embodying my new design.

FIGURE 2 is a side elevational view; and

FIGURE 3 is an end elevational view thereof.

The back of my trading stamp is flat in configuration and is blank.

The dominant feature of my design resides in the novel scroll work which includes a plurality of individual adjacent or overlapping loops connected together so as to form an elliptical over-all pattern with the central loops on the opposite sides of the center of the elliptical pattern being generally circular and the ellipse progressively increasing in size in both directions away from the center of the elliptical pattern substantially as shown.

I claim:

The ornamental design for a trading stamp, as shown and described.
